UNITED STATES PATENT OFFICE.

LOUIS W. LEVY, OF NEW YORK, N. Y.

DESIGN FOR A NEWSPAPER-HOLDER.

46,314.

Specification for Design.

Patented Aug. 25, 1914.

Application filed April 1, 1914. Serial No. 828,917. Term of patent 3½ years.

To all whom it may concern:

Be it known that I, LOUIS W. LEVY, a citizen of the United States of America, residing in the borough of Manhattan, city, county, and State of New York, have invented a new, original, and ornamental Design for a Newspaper-Holder, of which the following is a specification, reference being had to the accompanying drawing, forming a part hereof.

The figure is a perspective view of a newspaper holder, showing my new design.

I claim—

The ornamental design for a newspaper holder as shown.

Signed at New York, N. Y., this 30th day of March, 1914.

LOUIS W. LEVY.

Witnesses:

FRED WHITE,
THOMAS F. WALLACE.
